CLAIM

The ornamental design of a bank card with an ECG sensor, substantially as shown and described.

DESCRIPTION

FIG. 1 is a perspective view of a bank card with an ECG sensor in accordance with a first embodiment of the present invention;

FIG. 2 is a front view thereof;

FIG. 3 is a rear view thereof;

FIG. 4 is a side view thereof;

FIG. 5 is a perspective view of a bank card with an ECG sensor in accordance with a second embodiment of the present invention;

FIG. 6 is a front view thereof;

FIG. 7 is a rear view thereof; and,

FIG. 8 is a side view thereof.

The features shown in broken lines showing the remainder of the embodiments of the bank card with an ECG sensor are directed to environment and form no part of the claimed design.
